LUTHER GIBBS, OF FREMONT, OHIO.

Letters Patent No. 68,063, dated August 27, 1867.

IMPROVED LIME-KILN.

The Schedule referred to in these Letters Patent and making part of the same.

TO ALL WHOM IT MAY CONCERN:

Be it known that I, LUTHER GIBBS, of Fremont, in the county of Sandusky, and State of Ohio, have invented a new and useful improvement in Lime-Kilns; and I do hereby declare that the following is a full, clear, and exact description of the same, reference being had to the annexed drawings, making part of this specification, in which—

Figure 1 is a vertical transverse section.

Figure 2 is a vertical longitudinal section.

Figure 3 is a horizontal section on the line $z z$, fig. 2.

Figure 4 is a horizontal section on the line $y y$, fig. 2.

The same letters are employed in all the figures in the indication of identical parts.

A is the body of the kiln; B the furnaces, placed on each side, having doors B^1 . The fuel is burned upon the grate B^2 . C is the ash-pit, closed by a door, C' . D is the fire-chamber, into which the flame is carried from the furnaces on each side. Four flues, D' , are constructed in the fire-chamber, leading from the corners thereof into the cupola E. The draught through the side flues D' , in the sides of the fire-chamber, will cause the flame, in passing into the cupola when it is filled with stone, to be expanded, causing a more equal burning of the lime in the cupola. The "kettle" F is made rectangular, and, measured lengthwise, it is longer than the diameter of the cupola at its base, which is at the top of the fire-chamber. The object of this construction is to prevent the lime from lodging as it falls, after being burned, and clogging in the kettle. The draw-flues $G G^1 G^2$, closed by doors, are placed at the bottom of the kettle, which tapers towards the bottom. When the lime is drawn from the draw-flue G , the stones on that side will fall, leaving a surface above, exposed to the action of the fires. The same result will follow when it is drawn from the draw-flue G^2 ; when drawn from G^1 , the centre will fall. By means of this arrangement of the draw-flues the relative positions of the stones in the kiln may be varied as required during the process of burning.

What I claim as my invention, and desire to secure by Letters Patent, is—

A kiln for burning lime, when constructed with two furnaces, B B, and a central fire-chamber, D, in continuous line across the kiln, and with flues D' in the corners of the fire-chamber, and with a kettle, F, of greater longitudinal measurement than the diameter of the cupola E, and furnished with three draw-flues, $G G^1 G^2$, said parts being constructed and arranged for use in the manner set forth.

In testimony whereof I have signed my name to this specification in the presence of two subscribing witnesses.

LUTHER GIBBS.
